EXPANSION BRACELET FOR WATCHES

Charles J. Obst, Barrington, R.I., assignor to Flex-Let Corporation, East Providence, R.I., a corporation of Rhode Island

Filed Feb. 23, 1960, Ser. No. 59,544

Term of patent 14 years

(Cl. D45—4)

FIG. 1

FIG. 2

FIG. 3

FIG. 4

FIG. 5

I claim:

The ornamental design for an expansion bracelet for watches, substantially as shown.
